DRIVE MEANS FOR MECHANICAL HORSE

Lloyd E. Yetter, Colchester, Ill.

Application June 11, 1954, Serial No. 436,082

3 Claims. (Cl. 74—86)

This invention relates to a mechanical horse, and particularly to an actuating mechanism for a mechanical amusement or exercising device.

In the construction and operation of mechanical exercising devices such as mechanical exercising and amusement devices such as mechanical horses, it is customary to provide an actuating mechanism and to mount the device such as the mechanical horse thereon and to control the mechanism by means of a suitable frame control device so that the mechanism will actuate the exercising or amusement device for a predetermined length of time. It has heretofore been the practice to make the mechanical ride as nearly as possible simulate an actual ride in order to provide more exhilaration for the party taking a ride. Heretofore, these actuating mechanisms have been extremely complicated and it has been necessary to maintain corps of experienced workmen to maintain a quantity of the mechanical devices in continuous operation.

The present invention relates to a comparatively simple and inexpensive actuating mechanism to simulate a horse riding motion so that the maximum of entertainment or enjoyment may be secured from the ride thereon.

It is accordingly an object of the invention to provide a simplified ride actuating device.

It is a further object of the invention to provide an actuating device having few and simple parts.

It is a further object of the invention to provide an actuating device which may be readily mounted and maintained.

Other objects and many of the attendant advantages of the present invention will be apparent from the following detailed description taken in conjunction with the accompanying drawings in which:

Figure 1 is a perspective view of the mechanical ride device according to the invention;

Figure 2 is a top plan view of the actuating mechanism with the seat portion removed;

Figure 3 is a side elevation of the actuating device with the seating mechanism removed;

Figure 4 is a perspective view of the actuating device with the cover and seating mechanism removed;

Figure 5 is a sectional enlarged elevation of the rocker arm showing the adjustable connection therein;

Figure 6 is a fragmentary enlarged elevation showing the eccentric actuating device for the operating arm; and

Figure 7 is an enlarged end view of the control track with parts broken away and in section.

In the exemplary embodiment according to the invention, a housing 10 provides a cover over an actuating mechanism and a mounting standard 12 extends through a suitable aperture in the housing 10 and a ride device such as a horse 14 is mounted thereon. Preferably a horse is provided with a suitable seat in the form of a saddle 16 and a coin control device 18 mounted on a standard 20 is provided for controlling the mechanism in the cover 10.

The actuating mechanism according to the present invention comprises an elongated base member 22 preferably formed as a metallic plate of skeleton-like formation on which the mechanism proper is to be mounted. 5 A motor 24 is mounted adjacent one end of the base 22 preferably substantially centrally of the end of the plate. A speed reducing mechanism includes a sheave 26 on the shaft 28 of the motor 24 with the sheave 26 being of relatively small size and an idler sheave 30 is mounted 10 on an idler shaft 32 mounted in bearings 34 mounted on the base 22 by means of suitable uprights 36. A flexible tension member such as the V-belt 38 is entrained over the sheaves 26 and 30 and a tensioning roller 40 will be mounted on an arm 42 journaled on a pin 44 15 on a bracket 46 secured on the base 22 and tensioned against the member 38 by means of a spring 48. A main drive shaft 50 is mounted in bearings 52 and 54 secured on suitable standards 56 on the base 22. A driving sheave 58 is mounted on the drive shaft 50 and is connected to an intermediate sheave 60 on the idler shaft 32 and fixed to the sheave 30. A suitable tension drive element such as the V-belt 60 is entrained over the sheaves 58 and 60 and an idler roller 64 mounted on a pivoted arm 66 which is journaled on a bracket 68 on the base 22 is pressed into engagement with the belt 62 by means of a suitable tension spring 70. A disc 72 is rigidly mounted in eccentric relation on the shaft 50 for a purpose presently to be described.

The actuating mechanism proper includes a transverse plate 80 having substantially parallel arms 82 and 84 rigidly mounted adjacent the ends thereof by any suitable means such as welding, with the arms 82 and 84 extending longitudinally of the plate 22 and beyond the confines of the plate 22 in substantially parallel relation. 30 Axle pins 86 and 88 are threaded engaged in the ends of the arms 82 and 84, respectively, and secured by means of lock nuts 90 and 92, respectively. Rollers 94 and 96 are journaled on the stub ends 86 and 88 and engaged on suitable control tracks 100 and 102. The 35 control tracks 102 and 100 are mounted on a substantially integral mounting bracket 104 having an upstanding sidepiece 106 and an angulated base member 108 having a pair of elongated apertures 110 therein for receiving the fastening bolts 112. Track member 102 is provided with a shoulder or abutment 114 for preventing lateral movement of the rollers 96 thereon and the tracks 102 may be adjusted by means of the elongated slot 110 so that the rollers 96 will be maintained firmly on the tracks without any lateral movement. In order to prevent vertical movement of the rollers 96, an angulated hold-down member 116 is fastened on the flange portion 106 by any suitable means such as the stubs 118. The standard 12 to mount the seating mechanism of the device is rigidly mounted on the plate 80 adjacent the central portion thereof and preferably extending at a suitable angular relation thereto.

Plate 82 and the rest of the mechanism attached thereto is controlled by means of a two-part rocker arm having a section 120 rigidly connected to the plate 80 by any suitable means such as welding. A second section 122 is separated from the section 120 but rigidly secured thereto by an adjustable connection comprising a threaded rod-like member 124 rigidly secured on the member such as 120 and a nut-like member 126 rigidly secured on the other member such as the member 122 with the nut being rotatable to adjust the position of the member 122 with respect to the member 120.

The oscillatory motion of the device is produced by means of a bearing follower 130 mounted on the end of the section 122 and having a bearing 132 received therein by any suitable means such as the split 124 joined together by means of a bolt 136. The bearing 132 snugly

embraces the disc 72 and as the disc 72 rotates in the eccentric bearing, because of the rotation of the shaft 50 the end of the rocker arm 122 will form a peculiar eccentric gyration therewith.

In the operation of the device according to the invention, the motor 24 will be controlled for any suitable period of time by any suitable device such as the coin controller 18. When the motor is energized the gear train will reduce the speed so that the shaft 50 will be rotated at a desired rate of speed. The rotation of the shaft 50 will cause the eccentrically mounted disc 72 to turn in an orbit about the shaft 50 so that the follower 130 will be caused to take an annular path about the shaft 50. The rotation of the shaft 50 causing the annular motion of the member 130 causes the arm 120 and 122 to oscillate about the pivot pins 86 and 88 and also cause the rollers 96 to roll backward and forward on the tracks 102 giving a compound motion to the standard 12 and the top of the standard 12 will then perform a peculiar series of motions substantially simulating the trotting or galloping of a horse. For example, the horse member will come upwardly and forwardly at an increasing rate, then it will stop and come downwardly and rearwardly at a lesser rate so that the entire motion resembles the motion of a horse in running or galloping relation. Obviously, the extent of the motion may be controlled by the size of the disc 72 and by the amount of adjustment in the arms 120 and 122.

For the purpose of exemplification a particular embodiment of the invention has been shown and described according to the best present understanding thereof. However, it will be apparent to those skilled in the art that various changes and modifications may be made in the construction and arrangement of the parts thereof without departing from the true spirit and scope of the invention.

What is claimed as new is as follows:

1. An actuating mechanism for a mechanical horse comprising a base member, a pair of trackways mounted on said base member, said trackways being in spaced parallel relation, a pair of bearings mounted on said base member in longitudinally spaced relation to said trackways, a shaft journaled in said bearings, said shaft being disposed transversely to said trackways, a mounting frame, a pair of rollers journaled on said frame, said rollers being received in said trackways, a disk eccentrically fixed on said shaft, a bearing mounted on said frame and embracing said disk, an upstanding mounting standard fixed on said mounting frame intermediate said rollers and said shaft, and means for rotating said shaft, whereby compound vertical and longitudinal movement is imparted to said standard.

2. An actuating mechanism for a mechanical ride device comprising a base member, an actuating frame including a mounting plate, a pair of parallel arms fixed on said plate, adjacent the opposite ends thereof, said arms

extending from said plate, a roller mounted adjacent the outer end of each of said arms, a pair of trackways mounted on said base and receiving said rollers, said trackways being transversely adjustable on said base, a rocker arm fixed to said plate intermediate the ends thereof, said rocker arm extending in substantially parallel relation to said pair of arms, a pair of bearings mounted on said base in longitudinally spaced relation to said trackways, a shaft journaled in said bearings and extending transversely to said rocker arm, a disk eccentrically secured on said shaft, a bearing mounted on said rocker arm and embracing said disk, a mounting standard fixed on said plate in longitudinally spaced relation relative to said bearings, whereby compound vertical and horizontal movement is imparted to said standard.

3. An actuating mechanism for a mechanical ride device comprising a base member, an actuating frame including a mounting plate, a pair of parallel arms fixed on said plate, adjacent the opposite ends thereof, said arms extending from said plate, a roller mounted adjacent the outer end of each of said arms, a pair of trackways mounted on said base and receiving said rollers, said trackways being transversely adjustable on said base, a rocker arm fixed to said plate intermediate the ends thereof, said rocker arm extending in substantially parallel relation to said pair of arms, a pair of bearings mounted on said base in longitudinally spaced relation to said trackways, a shaft journaled in said bearings and extending transversely to said rocker arm, a disk eccentrically secured on said shaft, a bearing mounted on said rocker arm and embracing said disk, a mounting standard fixed on said plate in longitudinally spaced relation relative to said bearings, whereby compound vertical and horizontal movement is imparted to said standard, said rocker arm being discontinuous intermediate the ends thereof, an adjustable connection between the parts including a threaded rod rigidly mounted on one portion and extending across the discontinuity, a nut rigidly secured on the adjacent end, said nut being threadedly engaged on said threaded rod whereby the length of said rocker arm may be adjusted to vary the relation between the vertical and horizontal components of said compound movement.
